US00D613164S

(12) **United States Design Patent**
Lee

(10) **Patent No.:** US D613,164 S
(45) **Date of Patent:** ** Apr. 6, 2010

(54) **CELL PARTITION FOR PACKAGE**

(76) Inventor: **Yeong-Hee Lee**, 101-605, Donga 3-Cha Apartment, Pungdeokcheon 3-dong, Suji-gu, Yongin, 448-758 (KR)

(**) Term: **14 Years**

(21) Appl. No.: **29/333,447**

(22) Filed: **Mar. 10, 2009**

(51) **LOC (9) Cl.** 09-07

(52) **U.S. Cl.** D9/456

(58) **Field of Classification Search** D9/705, D9/635, 520, 517, 516, 456, 455, 454, 452, D9/444, 445, 438, 436, 435, 434, 433, 432, D9/416.499, 750, 751, 756, 758, 760, 762; D26/51; 428/138; 362/101; 229/404, 128, 229/110, 103.3, 120.24, 120.25, 120.26; 220/630; 206/776, 755, 754, 583, 522, 453, 206/390, 232, 193, 426, 427; D7/509, 511, D7/396.2, 624.2, 602
